US00D783666S

(12) **United States Design Patent** (10) **Patent No.:** **US D783,666 S**
(45) **Date of Patent:** **** Apr. 11, 2017**

(54) **DISPLAY SCREEN WITH GRAPHICAL USER INTERFACE**

(71) Applicant: **Microsoft Corporation**, Redmond, WA (US)

(72) Inventors: **John Snavely**, Seattle, WA (US); **Megan McMillan**, Seattle, WA (US); **MacBeth Watson**, Redmond, WA (US); **Chao Wang**, Seattle, WA (US); **David Gardner**, Covington, WA (US); **Eric Hsia**, Seattle, WA (US)

(73) Assignee: **Microsoft Corporation**, Redmond, WA (US)

(**) Term: **15 Years**

(21) Appl. No.: **29/535,306**

(22) Filed: **Aug. 5, 2015**

(51) LOC (10) Cl. **14-04**

(52) U.S. Cl.

USPC **D14/487**; D14/488; D14/489; D14/491; D14/492; D14/495

(58) **Field of Classification Search**

USPC D14/485-495

CPC .. G06F 3/04842; G06F 3/048; H04N 1/00424

See application file for complete search history.

(57) **CLAIM**

The ornamental design for a display screen with graphical user interface, as shown and described.

DESCRIPTION

The FIGURE is a front view of a display screen with graphical user interface showing our new design.

The broken line showing of the display device illustrates environment. The remaining broken lines illustrate portions of the graphical user interface. The broken lines form no part of the claimed design.
